UNITED STATES PATENT OFFICE

GLENN J. BARRETT, OF EVANSTON, ILLINOIS, ASSIGNOR TO PORTABLE ADDING MACHINE COMPANY, OF CHICAGO, ILLINOIS, A CORPORATION OF ILLINOIS

LISTING MECHANISM FOR ADDING MACHINES

Original application filed August 14, 1925, Serial No. 50,219. Divided and this application filed August 31, 1927. Serial No. 216,672.

This invention relates to improvements in listing mechanism for adding machines and has for its principal objects to provide simple and efficient means for printing amounts on a record sheet in accordance with the setting of numeral keys of the keyboard of the machine, to provide a printing mechanism operable automatically upon actuation of the general operator to list amounts during adding operations, to provide key-set means whereby the printing mechanism may be rendered ineffective to list amounts during adding operations, to provide improved means for taking impressions from aligned types on a plurality of type carriers differentially set in accordance with the setting of numeral keys of a key-set adding machine, to provide improved means for feeding and reversing the inked ribbon of the printing mechanism, to provide improved means for feeding the record strip through the printing mechanism, to provide efficient means for feeding a reeled inked ribbon and a reeled record strip intermittently past the impression line of the machine and pressing the same against types at the impression line through the medium of a platen and a vibratory platen support which is controlled from the general operator of the machine to shift the platen toward and from the type at each actuation of the general operator, and to provide means for taking an impression by a toggle connection between the general operator of the machine and a rocking platen support which is substantially at a dead center at the time the platen is pressed against the types, whereby the impression is taken by pressure rather than by impact.

To the foregoing and other ends, which will appear from the following description in detail of the preferred embodiment of the invention, the invention consists in the features of construction, arrangements of parts, and combinations of devices set forth in the specification and particularly pointed out in the appended claims.

In the drawings:

Fig. 1 is a side elevation of the machine with the outer casing or cover removed, certain of the operating parts being omitted to

more clearly show the listing mechanism, and the parts shown being illustrated in normal idle position;

Fig. 2 a fragmentary side elevation showing the non-print key set and the platen frame 55 rocking link in the position it occupies at the end of the forward stroke of the operating handle during non-print operations of the machine;

Fig. 3 a longitudinal sectional view of 60 the machine, showing the parts positioned as at the end of the forward stroke of the operating handle;

Fig. 4 a transverse sectional view in the vertical plane of the main shaft 68; 65

Fig. 5 a fragmentary view similar to Fig. 1 showing the parts positioned as at the end of the forward stroke of the handle during a printing operation of the machine;

Fig. 6 a perspective view showing the 70 platen and its rocking frame and associated devices;

Fig. 7 a side elevation of the rear part of the machine with the cover casing broken away, the platen and associated devices being 75 shown positioned as in Fig. 5;

Fig. 8 a perspective view of the paper roll supporting bracket;

Fig. 9 a perspective view of the paper roll supporting shaft or rod; 80

Fig. 10 a rear view of the machine substantially perpendicular to the printing plane with part of the cover casing broken away and the operating parts positioned as in Fig. 3; 85

Fig. 11 is a fragmentary central longitudinal sectional view of the machine showing the ribbon mechanism;

Fig. 12 a fragmentary view of the machine showing the ribbon mechanism and part of the platen support in elevation as viewed from the left hand side of the machine; 90

Fig. 13 a top plan view of the ribbon mechanism, partly broken away through the upper spool, showing the actuating arm of the dog carrier in its normal rear position and the feed-reversing mechanism in position for causing winding of the ribbon upon the upper spool; 95

Fig. 14 a view similar to Fig. 13 but show- 100

ing the actuating arm of the dog carrier in its forward position, as at the end of the forward stroke of the operating handle of the machine, ready for effecting a feed movement of the ribbon on the return stroke;

Fig. 15 a top plan view of the ribbon mechanism with the parts above the dog carrier broken away and the dog carrier positioned as in Fig. 14;

10 Fig. 16 a view similar to Fig. 13, showing the reversing mechanism set to reverse the direction of feed on the next forward stroke of the actuating arm of the dog carrier to cause winding of the ribbon from the lower 15 spool on to the upper spool;

Fig. 17 a view similar to Fig. 15, showing the reversing mechanism set to reverse the direction of feed on the return stroke of the actuating arm of the dog carrier to cause 20 winding of the ribbon from the upper spool onto the lower spool;

Fig. 18 a perspective view of parts of the ribbon reversing mechanism detached;

Fig. 19 a perspective view of the ribbon 25 mechanism supporting means and the ribbon guide detached from the casing; and

Fig. 20 a detail view on the line 20—20 of Fig. 17 showing the detent means for locking the feed reversing cams to rock with the dog 30. carrier.

This application is a division of my co-pending application, Serial No. 50,219, filed August 14, 1925, for improvements in adding machines, and only so much of the machine 35 shown and described in said co-pending application as is necessary for a full understanding of the subject matter claimed in this divisional application will be shown and described.

40 The machine has a base plate 1, to which rubber supporting feet 2 are attached, and said base plate has transverse bars 3 and 4 held thereto on its upper face adjacent its front and rear ends. Frame side plates 5 and 6 are secured to the ends of bars 3 and 4 and support the working parts of the machine, except the ribbon mechanism, which, as hereinafter described, is mounted on a cover casing 8.

50 Casing 8 has an open bottom to enable it to be fitted over the supporting framework and enclose most of the working parts of the machine, and said casing is held in place by screws 9 threaded into bars 3 and 4. The side 55 plates support various transverse frame rods, including rods 136, and other parts herein-after described.

The top wall of casing 8 has an upwardly and rearwardly extending front portion provided with an aperture 10 exposing the keyboard of the machine, and said top wall has a downwardly and rearwardly extending rear portion extending to the upper end of the rear wall of the casing. The front and rear 65 and side walls of the casing extend vertically.

The downwardly and rearwardly inclined top wall portion is provided with an aperture 11 through which extends a rocking platen support mounted on the framework as hereinafter described. The types 70 of the printing segments 69 when set side by side in the printing plane face upward and rearward and are exposed through aperture 11, and the platen 141 is movable forward and downward through said aperture against said types to take an impression therefrom. The aperture 11 extends part way down the rear wall of the casing, as shown, to afford clearance for a paper-roll supporting and paper-strip tensioning means and also to afford clearance for the paper roll and for passage of the paper strip from the roll to the platen, as hereinafter more fully described. The ribbon feeding, reversing, and guiding means are mounted on the downwardly and rearwardly extending top wall portion of casing 8 and the paper roll support is mounted on the rear wall of the casing, as more fully hereinafter described.

The numeral keys 18 of the keyboard are arranged in fore-and-aft extending rows of ten keys each, the keys 18 in each row having values "0" to "9", inclusive, from front to rear, and being mounted on the upper ends of plunger stems 19 suitably guided in the keyboard unit of the machine, as shown, and normally held elevated by springs 33. The lower ends of stems 19 form numeral stops for cooperating with corresponding numeral stop lugs on stop-carrying slide bars 86, when depressed, to arrest movements of differentially rotatable adding sectors 79 and differentially rotatable type segments 69 in accordance with the setting of numeral keys of the machine in adding and listing operations, as shown in Fig. 3 and more fully shown and described in the co-pending application referred to.

The type segments 69 have hubs 73 loose on the main operating shaft 68 of the machine and are adapted to be differentially rotated in accordance with setting of numeral keys 18. A bail 294 mounted on and driven from shaft 68 cooperates with shoulders 295 on the type segments on the return stroke of the operating handle to restore the segments to normal idle position by clockwise rotation, as viewed in Fig. 3, and permits counter-clockwise rotation of the segments on the forward stroke of the handle.

When the handle is in normal position the segments are locked against counter-clockwise rotation by noses 72 of pivoted locking stops 37 engaging in front of stop lugs 71 on the segments. Stops 37 are pivoted on a rod 36 of the keyboard unit and have lugs 40 co-acting with the front ends of the key-locking slide bars 28 of the flexible keyboard and are also connected with the slide bars 28 by springs 43. This connection is such that

when a key plunger stem 19 is depressed it contacts with the cam upper edge of its locking hook 29 on the slide bar 28 for that key row to slide the bar back until the hook 29 locks the key stem in stopping position and at the same time lifts nose 72 of stop 37 above the lug 71 of the associated segment, as shown in Fig. 3.

The adding sectors are loosely mounted on the hubs of the printing segments and are connected by links 84 with the stop-carrying slide bars 86. The adding sectors have short pin and slot lost-motion connections 80—81 with the type segments and are connected, 15 with the segments by normally distended transfer springs 82 while the type segments are connected with a frame bar 77 by normally distended springs 74 passing over hubs 73 of the segments. On the forward stroke 20 of the operating handle 196 of the machine the bail 294 swings rearward and the springs advance unlocked type segments to position types thereon at the printing line in accordance with the setting of the numeral keys, 25 the type segments being arrested by the key stems and the stop bars through the medium of their connections with the adding sectors.

The adding sectors have toothed rack portions 107 for coaction with the accumulator 30 108 of the machine which is mounted in a shiftable frame controlled from a cam disk 201 having its hub 199 fixed to shaft 68 by a pin 200. Main shaft 68 is journaled in frame plates 5 and 6 and is oscillated by the general operator of the machine which consists in the present instance of a crank handle 196 having a socket 197 interlocked with hub 199 of disk 201 and held in place by a locking screw 198 passing through the handle socket and screwed into the end of shaft 68. The types 70 on the printing segments are arranged in an arc normally facing rearwardly. Each segment carries types "0" to "9", inclusive, the "0" type being at the top and the "9" type at the bottom and all the type being normally below the printing line. Adding sectors 79 have stop lugs 120 cooperating with transfer devices 116 normally set to arrest return of the adding sectors before the bail 294 completes the return of the type segments to normal locked position. The keys are unlocked on the return stroke of the handle 196 by a suitable key releasing means 44—46—51 operated by a roller 221 on disk 201. The foregoing parts are all more fully shown and described in the co-pending application above referred to, as is the construction and operation of the adding mechanism, and the foregoing description will enable those skilled in the art to fully understand the type-setting operation of the machine.

Platen supporting means

The type 70 on the respective type segments 69 are rigidly held to the segments and

face radially outward toward the rear and are adapted to be printed on by a suitable platen 141, which is mounted for movement toward and from the type segments. The platen 141 has its shaft 159 rotatably mounted in platen frame side plates 142, which are secured together by transversely extending stay rods 143, 144 and 145, to form a rocking frame, which is mounted upon a transversely extending rock shaft 146 located adjacent the rear wall of casing 8 and journaled in the frame side plates 5 and 6. The platen frame side plates 142 extend up through aperture 11 in casing 8 and may be secured to or otherwise adapted to be rocked by rocking the shaft 146, but preferably, a hub 147 is mounted on the rock shaft 146, as indicated in Figs. 3, 6 and 10 of the drawings, and secured thereto by a set pin 148, the hub being provided with a depending arm 149 having a forked lower end engaged with the lowermost stay rod 145. A collar 150 is secured to the rock shaft 146 at the inner face of the left-hand side plate 142 to hold the platen rocking frame in spaced relation to the main frame side plates 5 and 6, a spacing collar 150^a being inserted between the outer face of left hand side plate 142 of the rocking frame and the main frame side plate 6, as indicated in Fig. 10. An additional collar 151 is secured to the left end of the rock shaft 146, outside the side plate 6, for preventing movement of the shaft toward the right, as viewed from the front of the machine. The side plates 142 of the platen rocking frame are 100 preferably provided with forwardly projecting lugs 152 adapted to engage a fixed transverse rod 153, mounted in the main frame plates 5 and 6, for limiting the rearward movement of the platen under the action of a spring 154, (see Figs. 1, 6 and 10) connected at one end to the lowermost stay rod 145, the other end extending toward the front of the machine and being suitably anchored to one of the transverse rods of the fixed framework of the machine, previously referred to. The pendent extremities of the platen frame side plates 142 below the shaft 146 are formed as stop fingers 155, adapted to cooperate with a transversely extending stop rod 156, for limiting the movement of the platen toward the type segments under the action of the operating handle, as hereinafter described. The stop rod 156 is preferably adapted to be adjusted up and down 120 by being mounted in vertical slots 157 in main frame side plates 5 and 6, as shown in Figs. 1, 3, 7 and 10, the stop rod being held in adjusted position by suitable clamping screws 158. By means of this adjustment, the pressure of the platen against the type 70 of the type segments may be regulated.

Line-spacing mechanism

I have provided simple and compact line-

spacing means for feeding a work piece over the platen step-by-step, which mechanism consists of few parts and is operable by the swinging movements of the platen frame.

5 The platen 141 is preferably secured to the platen shaft 159 by a suitable set screw 159^a in the hub 160 of the platen, and the right hand end of the platen shaft 159 is provided with the usual knurled knob or twirler 162
10 for manual rotation of the platen. The hub 161 at the right hand end of the platen is provided with a line space ratchet wheel 163, which is adapted to cooperate with the nose 164 of a line space pawl 165 pivoted at 166
15 to a stud 167 secured to the main frame plate 5, said pawl extending through aperture 11 in the casing, as shown in Figs. 1, 6, 7 and 10. A spring 168 is provided for urging the line space pawl toward the rear, the spring being
20 connected to the pawl and to a fixed pin 169 on frame plate 5, as shown in Figs. 1 and 10. Movement of the line space pawl 165 toward the rear is limited by a forwardly projecting finger 170 on the lower pivoted end of the
25 pawl which is adapted to engage under the stop rod 153, as indicated in Figs. 1 and 6. A detent roller 163^a is mounted on the lower end of a lever 163^b pivoted at 163^d on the platen frame and adapted to resiliently en-
30 gage the teeth of the line space ratchet 163, a spring 163^c being connected between the lever and a pin on the platen frame plate 142.

The arrangement just described is such
35 that, when the platen rocking frame is moved forward on the forward stroke of the handle 196 the nose 164 of the line space pawl 165 will be engaged by the ratchet wheel 163 and the pawl then rocked forward and downward
40 about its pivot 167 on the main frame to the position shown in Fig. 7, against the tension of spring 168, the nose of the pawl sliding back over one tooth of the ratchet wheel owing to the different centers about which the
45 platen and pawl rock, so that, as the platen rocking frame moves back to normal position on the return stroke of the handle, the platen will be rotated one line space by reason of the different pivoting of the pawl and platen
50 frame, and just before the platen rocking frame reaches normal position, the pawl 165 will be withdrawn from the ratchet wheel by the engagement of the finger 170 with the rod 153, and the platen will be held against accidental rotation by the detent roller 163^a. The
55 normal position of the parts is illustrated in Figs. 1 and 6.

Paper supplying, feeding, and guiding means

Paper supplying, feeding and guiding means are provided whereby a paper strip is unreeled from a supply roll and fed over the front of the platen 141. A deflector plate or apron and paper guide 171 is secured by screws 172 to the stay rod 144, immediately

below the platen, and extends in a semi-circular loop 173 around the front of the platen. The guide plate is cut out at 174, some distance below the printing line, to leave space for the type on the type segments to reach
70 the platen, or the paper thereon, for the printing operation. The ends 175 of the narrow strips of the paper guide, on each side of the printing line, are preferably bent upward and pass through holes 176 in a paper-tearing-off blade 177, which is secured to the uppermost stay rod 143 by ears 178 at its front end. The tearing-off blade 177 is rigidly held in position above the platen with its tearing edge rearmost by lugs 179, formed at the sides
75 thereof in rear of the stay rod 143, entering suitable holes in the platen frame plates 142, as shown in Figs. 1, 6 and 7.

The deflector plate 171, toward the front of the platen, is provided with elongated openings at 180, through which short metal feed rollers 181 are adapted to contact with the surface of the platen or with the paper thereon. The feed rollers 181 are preferably provided with knurled faces, and are freely
80 rotatable upon a transversely extending shaft 182, the reduced ends of which are loosely supported in short up-and-down extending slots in forwardly projecting arms 183 of a rocking feed roll frame 184, which straddles paper apron 171 and is pivotally mounted on the stay rod 144, as shown in Figs. 3, 6 and 10.

A spring 185 is coiled about the stay rod 144 and arranged so that one end extends under shaft 182 and engages a notch 186 in said shaft between the two feed rollers, while the other end engages in front of the depending edge of the guide plate 171, as will be seen in Figs. 3 and 6 of the drawings. In this manner, the feed rollers 181 are resiliently held for feeding engagement with the platen, and preferably, the rocking frame 184 is provided with rearwardly and upwardly extending finger pieces 187, which may be moved forward to rock the feed roll frame about stay rod 144
90 for releasing the feed rollers from the platen when it is desired to adjust the paper.

The platen 141 is preferably short, so as to accommodate merely a narrow strip or ribbon of paper, adapted to be drawn from a paper roll 188. The roll of paper 188 is removably mounted upon a supporting shaft 189 provided with annular grooves 190 at the ends thereof, in which are adapted to engage the edges of slots 191 in a paper-roll-supporting bracket 192. The paper roll bracket is secured to the rear lower edge of the cover casting 8 below the aperture 11 in the casing, by suitable screws 193. The slots 191 in the paper roll bracket 192 extend upward and rearward at a relatively sharp angle, so as to provide a gravity feed of the roll 188 to keep the roll of paper in contact with a friction roller 194, rotatably mounted in the forward ends of extensions 195 of the roll-holder
110 120 125 130

bracket 192 which project forward through the lower end of aperture 11 in casing 8. This arrangement enables the paper to be readily drawn from the roll 188 at the upper side of said roller 194 upward and over the deflector plate 171, the tension on the paper strip being regulated by the pressure of the roll of paper against the friction roller 194.

The roller 194 is preferably placed close to the rock shaft 146 on which the platen-rocking frame is mounted. The paper always runs from above the roller 194 to the platen so that the relation of the paper to the platen remains the same without regard to the diameter of the roll of paper. The paper, therefore, will be fed under uniform conditions at all times; and by placing the roller 194 close to the pivotal axis of the platen rocking frame no material slack will be developed in the paper strip between the platen and the roller because of the oscillations of the platen rocking frame. Any slight slack developed will be taken up by the feeding of the paper around the platen.

25 Ribbon mechanism

To provide a satisfactory ribbon mechanism for machines of this type is a difficult problem, particularly as the space is limited and it is desirable to provide not only for the satisfactory feeding of the ribbon, but also to provide for the automatic reverse of the feed, which will not require any attention on the part of the operator. I have provided a compact and simple ribbon mechanism operable by the shifting platen frame. A bracket 329 for the ribbon mechanism is mounted on the rearwardly and downwardly inclined rear portion of the top wall of the 40 cover casing 8, at the left hand side edge of aperture 11 in the casing and secured to said portion of the casing by suitable screws 330, as indicated in Figs. 4, 10 and 12 of the drawings. The bracket 329 is provided at its lower 45 edge with an upwardly and rearwardly extending plate 331, provided with a rod or shaft 332, projecting laterally therefrom upwardly and forwardly and forming the axle for a pair of ribbon spools 333 and 334, which 50 are held in place thereon by suitably spaced sealing clips (not shown) and a screw 335, threaded in the end of the axle rod 332 and cooperating with a washer 336.

The ribbon spools 333 and 334 are spaced 55 apart on the axle 332, and pivotally mounted therebetween on said axle is a ribbon feed dog-rocker 337 provided with a laterally projecting rock-arm 338. The rock-arm 338 is provided with an ear 339 adapted to be engaged and rocked forward by a pin or stud 340, projecting from the left hand platen-rocking frame plate 142, to rock the dog rocker about axle 332 to the position shown 60 in Fig. 14 from its normal position shown in Fig. 13. A rearwardly projecting ear 341

on the dog rocker is provided with two feed dogs 342 and 343, pivotally mounted thereon on a stud 344, the feed dogs being adapted to cooperate with ratchet teeth 345, formed on the peripheries of adjacent spool flanges of the ribbon spools 333 and 334. The dog rocker 337 is provided with an arm 346 projecting laterally outward and provided with a hole 347 in the end thereof, in which one end of a dog-rocker return spring 348 is secured. The opposite end of the spring 348 is secured to a laterally projecting lug 349 on the base of a small bracket 355 secured to the base of bracket 329, as indicated in Figs. 13 and 17. The dog-rocker return spring 348 is adapted to restore the dog rocker to normal position, shown in Fig. 13 after it has been moved or rocked to the position shown in Fig. 14 by engagement of the pin 340 on the platen-rocking frame with the dog rocker ear 339. The dog rocker 337 is further provided with a stop finger 350 adapted to engage a rod 351 held to bracket 329 parallel with axle rod 332 to thereby limit the return movement of the dog rocker under the action of the spring 348. The noses 358 of dogs 342 and 343 are adapted to be urged toward the ratchet teeth 345 of the respective ribbon spools by means of springs 352 connected to the respective dogs and to the dog rocker arm 346 in the hole 247, as indicated in Figs. 10, 12, 14 and 15.

Detent dogs 353 are pivotally mounted on a rod 354 mounted in the ears of the small bracket 355, secured to the main ribbon supporting bracket 329, the detent dogs being formed with laterally projecting pins 356, adapted to cooperate with the ratchet teeth 345 of the respective ribbon spools 333 and 334. Obviously, in feeding the ribbon in one direction or the other, only one of the feed pawls 342 or 343 will be in operation at a time, and the ribbon spool not being fed by its feed dog should be left free for independent rotation as the ribbon is unreeled therefrom by the action of the feed dog of the other spool on its spool. Therefore, the detent dogs 353 are provided with overhanging ends 357 adapted to lie above the laterally bent noses 358 of the respective feed dogs 342 and 343, so that when the feed dog of either spool is lifted out of operative relation with the teeth of the corresponding ribbon spool, the detent dog 353 associated therewith will also be lifted out of the field of the ratchet teeth, as shown in Fig. 16. The detent dogs 353 are preferably resiliently held in cooperative relation with the feed dogs and ratchet teeth of the respective ribbon spools by means of suitable springs 359 connecting the detent dogs with ribbon followers of the automatic feed reversing means, as herein-after described.

In order to provide means for holding one or the other of the ribbon feed dogs 342-343

out of operative engagement with its corresponding ribbon spool, a pair of cam plates 360 and 361 are mounted upon the axle 332, one on each side of the dog rocker 337.

5 The cam plate 360 is provided with a cam edge 362 having a dwell portion at one end and cooperating with the nose 358 of the feed dog 342, while the cam plate 361 is provided with a cam edge 363 having a dwell portion at 10 one end and cooperating with the bent end 358 of the feed dog 343. The two cam plates 360 and 361 are rigidly secured together by a tie rod 364, so that when cam plate 361 is moved about axle 332 by means of an outwardly projecting manual ribbon-reversing finger piece 365, formed as part thereof, the other cam plate 360 will also be moved, and the arrangement is such that when the cam edge 363 is moved under its dog, the cam edge 15 362 will be moved out from under its dog, thereby permitting the latter to operate in the ratchet teeth 345 of its ribbon spool, for feeding action of the ribbon, when the dog rocker 337 is operated.

20 Obviously, the cam plates 360 and 361 should rock with the dog rocker 337, in order to maintain one of the feed dogs 342 and 343 in operative position and the other feed dog in inoperative position and, therefore, a detent, operating between the cam plates and the dog rocker 337, is provided consisting of a spring pressed pin 366 in the dog rocker 337, cooperating with two positioning holes 366^a, located in the cam plate 360. When the 25 cam plates are in the position shown in Fig. 13 the dwell of cam edge 362 is under the nose 358 of the dog 342, and the nose of said dog 342 and the detent pin 366 of the corresponding detent dog 353 are held out of operative relation with the ratchet teeth 345 of the ribbon spool 333, so that the ribbon 376 will be wound on the upper spool 334. When the cam plates are shifted to the position shown in Fig. 16, the dwell of cam edge 363 is engaged under the nose 358 of dog 343 and holds the nose of said feed dog and the detent pin 366 of its corresponding detent dog 353 out of operative relation with the ratchet teeth 345 of the upper spool 334, so 40 that the ribbon 376 will be wound on the lower spool 333. The feeding or spool-rotating action of the dog rocker 337 always takes place under the action of the dog-rocker return spring 348 upon the return movement of the 45 platen-rocking frame, the return movement of the dog-rocker being limited by engagement of the finger 350 with the shaft 351.

An automatic ribbon reverse is an exceedingly desirable feature, in machines of this 50 character, for the machine may be operated indefinitely without requiring the operator to watch the ribbon and reverse the feed thereof when necessary. Therefore, in connection with my improved ribbon feed mechanism, I have provided an automatic reverse,

which comprises means for automatically shifting the cam plates 360 and 361, through the medium of the dog rocker operated by the platen-rocking frame.

For this purpose, ribbon-following fingers 55 367 are pivotally mounted on the shaft 351, and the springs 359, previously referred to as connected with the detent dogs 353, are secured to lugs 368 on the hubs of the ribbon-following fingers, so as to resiliently hold the 60 respective following fingers in contact with the reeled ribbon on the ribbon spools. In this manner, the following fingers 367 are adapted to move toward and from the spool centers as the reeled portion of the ribbon on 65 the respective spools decreases or increases in diameter, and this motion of the following fingers is utilized for moving dogs 369 and 370 respectively carried on the hubs of the following fingers of the upper and lower 70 spools and provided respectively with oppositely extending ears 371 and 372. The cam plates 360 and 361 are provided with operating fingers 374 and 373 respectively 75 adapted to cooperate with the ears 371 and 372, when the latter are thrown into the paths thereof by movement toward the center of the spools of the associated following fingers 367. As will be seen in Fig. 18, the cam operating finger 373 is provided with a squared end, 80 adapted to abut against the ear 371 when said ear is moved outward in its path, as shown in Fig. 16, while the cam finger 374 is provided with a hook end 375 adapted to hook under the ear 372 when said ear is thrown 85 outward into its path, as shown in Fig. 17.

It will be recalled that the rigidly connected cam plates 360 and 361, carrying the 90 respective operating fingers 374 and 373, are yieldably locked to rock with the dog rocker 337, each time the dog rocker is operated by the pin 340 on the platen-rocking frame. Hence, when the automatic reversing mechanism is set by substantial exhaustion of the 95 ribbon from the upper spool 334 in the position shown in Fig. 16, with the ear 371 moved outward so as to lie in front of the end of the finger 373 of cam plate 361, the parts are in 100 position to reverse the feed when the rock arm 338 is operated by the pin 340. When the dog rocker 337 is rocked by the pin 340 it will move as usual to the position shown in Fig. 14 but the cam plates 360 and 361 will be prevented from moving therewith at this time by the engagement of the operating finger 373 with the dog ear 371; thus the cam plates will 105 be shifted relatively to the dog rocker and dogs and the cam 362 will be brought into the position shown in Fig. 15 to lift the feed dog 342 upon the dwell of cam edge 362, thereby preventing further rotation of the ribbon spool 333 by said dog, while the cam edge 363 of cam 361 will be withdrawn from support of the dog 343 and the latter, under the pull of its spring 352, will be brought into feeding 110

relation with the corresponding ratchet teeth 345 of its ribbon spool 334, as indicated in Figs. 13 and 14. When the following finger 367 of the spool 333 reaches the position shown in Fig. 17, that is, when the spool becomes nearly empty, the corresponding dog 370 is moved outward to bring its ear 372 into the throat of hook 375 of the operating finger 374 carried by the cam plate 360, as shown, so that, upon the return movement of the dog rocker 337 from the position shown in Fig. 17, the spring 348 will restore the dog rocker to normal position, but the dog ear 372 will hold the cam plates 360 and 361 from movement with the dog rocker at this time, thereby shifting the relative position of the cams and dog rocker and placing the dwell of cam edge 363 under the nose of the dog 343, thus lifting the latter, and its cooperating detent dog 353, out of cooperative relation with the corresponding ratchet teeth 345 of the spool 334 while cam edge 362 will be withdrawn from the nose of dog 342 to permit the said dog and its detent to cooperate with the teeth of spool 333 and thereby again reverse the feed.

The ribbon 376 is carried between the respective ribbon spools over a ribbon guide plate 377, which is mounted, by means of ears 378, on the rearwardly and downwardly slanting portion of the cover casing 8, as shown in Fig. 10, the ears 378 being located in depressions 379 in the cover casing at the horizontal upper edge of the opening 11 therein. The ribbon guide 377 is secured to the casing 8 by suitable screws 380, so as to lie across the upper part of aperture 11 in a plane parallel to the printing plane of the types 70 on type segments 69 when at the printing line. The ribbon 376 is adapted to pass through two aligned slots 381 at the left hand end of the guide plate and over two right angle direction changing edges 382 at the right hand end of said plate so that the ribbon will pass from one spool to the other and lie in parallel bands extending from the spools over the ribbon guide across the aperture 11, the lower band of the ribbon passing over the printing line of the types, so that it is adapted to be between set types and the paper when the platen is moved forward in the printing operation. The upper ribbon spool 334 of the ribbon mechanism is preferably provided with a small knob 383 for manually winding the ribbon, when it is necessary to do so, for instance, in taking out an old ribbon and putting in a new one.

Platen support operating means

The cam disk 201 which operates the shiftable supporting frame for the accumulator of the machine, is also utilized for operating the rocking platen-supporting frame for moving the platen toward and from the type segments in the printing operation. For this purpose, a link or pitman 222 is pivotally

mounted on a stud 223 carried by the cam disk 201 and normally located forward of the axis of rotation of the main or handle shaft 68 on which the disc is fixed, as indicated in Fig. 1, the link normally extending 70 downward and rearward from said stud at such an angle that the disc and link have a toggle action which brings the pivot 223 substantially into a straight line between the shaft 68 and the rear end of the link when 75 the handle is at the forward end of its stroke, as shown in Fig. 5. The rear end of the pitman or link 222 is provided with a laterally and inwardly projecting stud 224, preferably mounted for slight adjustment and secured 80 in place by a lock nut 225. The inwardly projecting end of stud 224 is adapted to normally ride in an elongated notch or open top slot 226 in the lower extremity of a crank arm 227, secured to the outer end of the platen frame rock shaft 146, the arrangement being such that there is a certain amount of lost motion during the first part of the forward stroke of the handle 196, before the stud 224 will engage the rear end of the open 90 slot 226 and rock the platen frame to swing the platen toward the printing point. The toggle action, of the disk and link, near the end of the forward stroke of handle 196, as the pivot 223 brings the link or pitman to 95 dead center, will force the platen against the type segments for pressure printing upon the paper strip 188 of those numeral types on the segments that stand at the printing line. The amount of pressure required for printing varies with the number of segments to be printed from, and the adjustment of the stud 224 is adapted to be made according to the pressure required. It has been previously pointed out, however, that, in order to positively 100 limit the movement of the platen against the type segments, the lower extremities 155 of the platen rock frame are adapted to engage the transversely extending stop rod 156 to thereby prevent excessive pressure when only 105 a few type segments are to be printed from. The link or pitman 222 and its stud 224 are preferably held in proper relation with the open slot 226 in the crank arm 227, by a vertically slotted bracket plate 228 secured to 110 the side of the crank arm 227, the slot being elongated to allow upward movement of the rear end of the link. On the return stroke of the operating handle 196 the platen-frame restoring spring 154 returns the platen and 115 its frame to normal position and holds it there as hereinbefore described.

It is frequently desirable in machines of this type to operate the machine without printing the numbers, and this is usually effected by providing a special mechanism operated or controlled by a non-print key. In the present instance it will be seen that, if the stud 224 on the end of the pitman or link 222 is lifted out of the open slot 226, the 120

rock arm 227 will not be operated on the forward stroke of the handle and, hence, the platen will not be moved forward for printing. Therefore, the stud 224, at its inner end, is provided with a pin 229 projecting through an opening in the side plate 5 to engage the downwardly and rearwardly curved upper edge portion 242 of the rear end of a lever 230, pivoted at 231 on frame plate 5, as shown in Fig. 1. The lever 230 is located just inside the right frame plate 5 of the machine and the forward end 232 thereof is offset through an aperture 233 in said plate so as to lie outside of the frame plate, as indicated in Fig. 1. The forward end 232 of the lever is provided with an outwardly projecting stud or pin 234, passing through an elongated slot or opening 235 in the lower end of a non-print key-carrying plunger 236, which extends upward through a slot 237^a in a laterally projecting shelf-like plate or bracket 237, secured to the side frame plate 5, substantially parallel to the keyboard as will be seen in Fig. 1. Preferably the pin 234 is floatingly mounted in the slot 235 in the key plunger, by means of two springs 238 and 239, each connected to the pin 234, the lower spring 238 being connected at 240 to the lower end of the key-plunger, while the upper spring 239 is connected at 241, with the shelf 237, as indicated in Fig. 1. This connection is desirable because of the resistance at the rear end 242 of the lever 230 when attempting to lift the stud 224 before operating the handle. The rear end of the lever 230 is provided with an arcuate edge at 242 to permit the pin portion 229 of stud 224 on the end of the link 222 to remain in notch 226 when the non-print key is in normal position and to slide over the notch 226, during an operation of handle 196, when the forward end 232 of the lever is pulled down by the spring 238 after a depression of non-print key-plunger 236. The key-plunger 236 is preferably provided with a notch 243, adapted to receive the shelf plate 237 at the rear end of slot 237^a when its key is depressed to hold the key-plunger in depressed position.

This arrangement enables the key plunger 236 to be depressed and latched down before the handle 196 is started, the lower spring 238 being extended thereby, and as soon as the handle is started, the front end of lever 230—232 will be drawn down to the position shown in Fig. 2, thereby lifting the stud 224, so that it will ride over the open top of the slot 226 on the edge 242 of the lever without moving the platen frame rock arm 227. The position of the rear end of the pitman link 222, at the end of the forward stroke of the handle, when the non-print key is in depressed position, is shown in Fig. 2.

Obviously, one advantage of operating the line-spacing mechanism and the ribbon feeding mechanism by means of the platen-rock-

ing frame 142, is that, when the non-print key is depressed to eliminate the printing of a number by preventing rocking of the platen frame, operations of the line-spacing mechanism and the ribbon feeding mechanism are automatically eliminated at the same time. 70

It will be observed that I have provided an adding and listing machine wherein the listing mechanism is of simple and compact construction particularly suitable for small portable machines; that I have provided simple and efficient means for listing numbers on a record strip so constructed that the last listed number is readily visible after each actuation of the machine; that the listing mechanism may be put out of action when desired; and that the several devices coating for recording or listing numbers on a record strip are so constructed, arranged and operated as to reduce the number of parts to a minimum and to function in an efficient manner. 85

What I claim is:

1. In a key-set adding and listing machine, the combination of a main frame, a general operator for the machine, numeral keys, a plurality of type segments mounted on the main frame, numeral types rigidly affixed to said segments and normally facing toward the rear of the machine, means whereby said segments are differentially moved from normal position in accordance with the setting of the numeral keys to present selected types side by side with their faces in a printing plane inclined downward and rearward and then restored to normal position upon actuation of the general operator, a casing for the machine having a top wall the rear portion of which extends downward and rearward and is provided with an aperture through which types in the printing plane are exposed, a platen located above said aperture and movable therethrough against types in the printing plane, an inked ribbon feeding mechanism mounted on the downward and rearward extending top wall portion of the casing adjacent one side of said aperture, a ribbon guide mounted on said top wall portion of the casing above said aperture and projecting over said aperture for supporting a portion of the ribbon over the printing plane of the types and in a plane substantially parallel with the printing plane, a rocking support mounted on the main frame and extending up through said aperture and in which the platen is journaled, 110 means operable from the general operator for rocking said support to swing the platen forward and downward through said aperture against types in the printing plane, means for actuating the ribbon feeding mechanism 115 from the platen support, and line-spacing means for rotating the platen operable by rocking movements of the platen support. 120

2. In a key-set adding and listing machine, the combination of a main frame, a general 130

operator for the machine, numeral keys, a plurality of type segments mounted on the main frame, numeral types rigidly affixed to said segments and normally facing toward the rear of the machine, means whereby said segments are differently moved from normal position in accordance with the setting of the numeral keys to present selected type side by side with their faces in a printing plane inclined downward and rearward and then restored to normal position upon actuation of the general operator, a casing for the machine having a top wall the rear portion of which extends downward and rearward and is provided with an aperture through which types in the printing plane are exposed, a platen located above said aperture and movable therethrough against types in the printing plane, an inked ribbon feeding mechanism mounted on the downward and rearward extending top wall portion of the casing adjacent one side of said aperture, a ribbon guide mounted on said top wall portion of the casing above said aperture and projecting over said aperture for supporting a portion of the ribbon over the printing plane of the types and in a plane substantially parallel with the printing plane, a rocking support mounted on the main frame and extending up through said aperture and in which the platen is journaled, means operable from the general operator for rocking said support to swing the platen forward and downward through said aperture against types in the printing plane, means for actuating the ribbon feeding mechanism from the platen support.

3. In a key-set adding and listing machine, the combination of a main frame, numeral keys, a general operator for the machine, a plurality of type segments pivotally mounted on the main frame, numeral types rigidly affixed to said segments and normally facing toward the rear of the machine, means whereby said segments are differentially moved from normal position in accordance with the setting of the numeral keys to present selected types side by side with their faces in a printing plane inclined downward and rearward and then restored to normal position upon actuation of the general operator, a casing for the machine having a rear wall and also a top wall the rear portion of which extends downward and rearward to the rear wall, said casing having an aperture extending partly through the rear wall and said downward and rearward extending top wall portion, and through the upper portion of which types in the printing plane are exposed, a platen normally located above said aperture and movable therethrough against types in the printing plane, a rocking platen support pivoted on the main frame adjacent the rear wall of the casing and extending up through said aperture and in the upper part of which the platen is journaled, a paper roll support held to the rear wall of said casing for supporting a roll of paper at the lower end of said aperture close to the pivotal axis of the platen support for passage through the casing aperture to the platen, means on the platen support for guiding paper from a roll on the paper roll support over the front of the platen and holding the same to move toward and from the types with the platen, means operable upon actuation of the general operator for rocking the platen support to swing the platen downwardly and forwardly against types in the impression plane and restore the platen to normal position, line-spacing mechanism operable by rocking movement of the platen support for rotating the platen to unroll paper from a roll on the paper support and feed the same past the platen, and means operable by rocking movements of the platen support for feeding an inked ribbon between the platen and the impression plane of the types.

4. In a key-set adding and listing machine, the combination of a main frame, numeral keys, a general operator for the machine, a plurality of type segments pivotally mounted on the main frame, numeral types rigidly affixed to said segments and normally facing toward the rear of the machine, means whereby said segments are differentially moved from normal position in accordance with the setting of the numeral keys to present selected types side by side with their faces in a printing plane inclined downward and rearward and then restored to normal position upon actuation of the general operator, a casing for the machine having a rear wall and also a top wall the rear portion of which extends downward and rearward to the rear wall, said casing having an aperture extending partly through the rear wall and said downward and rearward extending top wall portion, and through the upper portion of which types in the printing plane are exposed, a platen normally located above said aperture and movable therethrough against types in the printing plane, a rocking platen support pivoted on the main frame adjacent the rear wall of the casing and extending up through said aperture and in the upper part of which the platen is journaled, a paper roll support held to the rear wall of said casing for supporting a roll of paper at the lower end of said aperture close to the pivotal axis of the platen support for passage through the casing aperture to the platen, means on the platen support for guiding paper from a roll on the paper roll support over the front of the platen and holding the same to move toward and from the types with the platen, means operable upon actuation of the general operator for rocking the platen support to swing the platen downwardly and forwardly against types in the impression plane and restore the platen to normal position, line-spacing mechanism operable by rocking movement of the platen support for rotating the platen to unroll paper from a roll on the paper support and feed the same past the platen, and means operable by rocking movements of the platen support for feeding an inked ribbon between the platen and the impression plane of the types.

forwardly against types in the impression plane and restore the platen to normal position, and line-spacing mechanism operable by rocking movement of the platen support for rotating the platen to unroll paper from a roll on the paper support and feed the same past the platen.

5. In an adding and listing machine, the combination of a general operator for the machine, numeral keys, type carriers movable in fixed paths and each provided with a set of fixed numeral types, means operable upon actuation of the general operator to move the carriers to present types side by side in a common impression plane in accordance with the setting of the numeral keys and subsequently restoring the carriers, a platen normally out of the impression plane, a shiftable platen support, means including 10 a pitman link driven by the general operator and connected with the platen support for shifting the platen against types in the impression plane, and a spring connected with the platen support for yieldably holding the 15 platen out of the impression plane.

6. In an adding and listing machine, the combination of a general operator for the machine, numeral keys, type carriers movable in fixed paths and each provided with a set of fixed numeral types, means operable upon actuation of the general operator to move the carriers to present types side by side in a common impression plane in accordance with the setting of the numeral keys 20 and subsequently restoring the carriers, a platen normally out of the impression plane, a shiftable platen support, means including a pitman link driven by the general operator and connected with the platen support 25 for shifting the platen against types in the impression plane, a spring connected with the platen support for yieldably holding the platen out of the impression plane, and normally ineffective key-actuated means effective 30 on said link when actuated to shift said link to a position in which it is ineffective to transmit movement to the platen support when the general operator is actuated.

7. In an adding and listing machine, the combination of a general operating handle for the machine, numeral keys, type carriers movable in fixed paths and each provided with a set of fixed numeral types, means operable upon actuation of the operating handle 35 to move the carriers to present types in accordance with the setting of the numeral keys side by side in a common impression plane, a platen normally out of the impression plane, a shiftable support for the platen, and a direct toggle connection between the operating handle and the platen support for forcing the platen against types in the impression plane.

8. An adding and listing machine as 40 claimed in claim 7 wherein the toggle con-

nection is so arranged as to be approximately on a dead center when the platen is forced against the types.

9. An adding and listing machine as 45 claimed in claim 7, having key-set means for disconnecting the toggle from the platen support at will.

10. In an adding and listing machine, the combination of a general operator, numeral keys, types, means operating upon an actuation of the general operator to position types in accordance with the setting of the keys side by side in a common impression plane, a platen normally out of the impression plane, a shiftable platen support, a connection between the general operator and the platen support for moving the platen to the impression plane, and adjustable stop means operating with the platen support for positively limiting movement of the platen toward the impression plane.

11. In an adding and listing machine, the combination of a general operator, numeral keys, types, means operating upon an actuation of the general operator to position types in accordance with the setting of the keys side by side in a common impression plane, a platen normally out of the impression plane, a horizontal rock shaft, a pair of transversely spaced members held to rock with 50 said shaft and in which the platen is supported at one side of said shaft, said members having stop fingers at the opposite side of said shaft, an adjustable stop member engageable by said stop fingers to positively 55 limit movement of the platen toward the impression plane, and a connection between the general operator and said rock shaft for 60 rocking the shaft to swing the platen to the impression plane.

12. In a key-set adding and listing machine, the combination of a series of type carriers each provided with a set of fixed numeral types, means supporting the carriers for differential movement in fixed paths to 65 position types in accordance with the setting of the numeral keys of the machine side by side in a common impression plane, a platen extending across the series of type carriers and normally out of the impression plane, 70 and toggle mechanism for moving the platen against types in the impression plane and arranged so as to be approximately on a dead center when the platen is pressed thereby against the types.

13. In an adding and listing machine, the combination of a general operator for the machine, a platen, a series of differentially movable type carriers arranged side by side and each provided with a set of fixed numeral types normally below the platen and facing rearwardly, general-operator-controlled means for moving the carriers upwardly and forwardly to align selected types in a common printing plane facing upwardly and rear-

- wardly toward the platen and subsequently restoring the carriers, means for supporting a work piece over the front of the platen to move toward and from the types with the 5 platen, general-operator controlled means for moving the platen forward and downward to force a part of the work piece at the front of the platen against the types aligned in the impression plane and then retracting the 10 platen to expose the impression on the work piece, means for supporting an inked ribbon on the main frame over the impression plane in front of the platen, means for feeding the ribbon during retraction of the platen 15 operable by said general-operator-controlled platen moving means, and means for line-spacing the work piece during retraction of the platen operable by said general-operator-controlled platen moving means.
- 20 14. In a key-set adding machine, the combination of a general operator for the machine, type carriers differentially movable upon actuation of the general operator to position types in accordance with the setting 25 of the numeral keys of the machine side by side in a common impression plane, a pivoted platen support, a rotatable platen journaled in said support, general-operator-controlled means for vibrating the support to move the 30 platen to and from the impression plane at each operation of the general operator, a line-space ratchet held to rotate with the platen and vibrate therewith, a line-space pawl pivotally supported independently of the 35 pivoted pattern support to swing about a different axis, a spring urging said pawl toward the ratchet wheel, and a stop engageable by said pawl to normally hold the pawl out of engagement with the ratchet and in position 40 to be engaged and rocked by the ratchet in opposition to said spring as the platen is moved toward the impression plane.
15. In an adding and listing machine, numeral types, type setting means, a rotatable 45 platen, a pivotally mounted platen support having side plates in which the platen is journaled and a stay rod connecting said side plates located below the platen, means for rocking the platen support to move the platen 50 toward and from set types for taking an impression, a pair of paper feed rollers located adjacent opposite ends of the platen below the platen, a feed roller frame pivoted on the stay rod, a shaft for the feed rollers mounted 55 in said frame for limited movement independently of the frame toward and from the platen, a spring mounted on the stay rod and engaging under the shaft between the feed rollers for resiliently pressing the feed rollers 60 against the platen, a paper guide mounted on the stay rod and extending around the front of the platen, a paper tearing plate mounted on the platen support above the platen with 65 which the upper end of the paper guide is connected, means for supporting a paper roll 70 adjacent the pivotal axis of the platen support for unreeling of the paper between the platen and the paper guide and feed rollers and tearing plate, and means operable by rocking movements of the platen support for rotating the platen to unreel paper step by step from a roll on the paper roll support.
16. In an adding and listing machine, numeral types, type-setting means, a rotatable platen, a pivotally mounted platen support in 75 which the platen is journaled, means for rocking the platen support to move the platen toward and from set types to take an impression, a friction drag roller mounted adjacent to and parallel with the pivotal axis 80 of the platen support, means for supporting a roll of paper for sliding movement by gravity against said drag roller, means on the platen support for guiding an unreeled portion of the paper roll over the platen and 85 holding it to move with the platen toward and from the types, and means operable by the rocking movements of the platen support for rotating the platen step by step to unreel paper from the paper roll.
17. In a key-set adding machine, the combination of a plurality of differentially movable type carriers, a set of numeral types rigidly held to each type carrier, numeral 90 keys, a general operator for the machine, means controlled by said general operator for moving the carriers in accordance with the setting of the numeral keys to position types side by side in a common printing plane and then restore the carriers, a platen, a shiftable support on which the platen is mounted, 95 general-operator controlled means for shifting said support to move the platen toward and from the type carriers for printing numbers, a ribbon supporting and feeding mechanism for feeding an inked ribbon between the platen and the printing plane mounted independently of the platen support, and means carried by the platen support for actuating the ribbon feeding mechanism.
18. In an adding and listing machine, numeral types, type-setting means, a platen, a shiftable support on which the platen is mounted, means for shifting the support to move the platen to and from set types for 100 taking an impression therefrom, and means mounted independently of the platen support and operable by the shifting movements thereof for supporting and feeding an inked ribbon between the platen and the impression-taking position of the types.
19. In a key-set adding and listing machine, the combination of a general operator for the machine, numeral keys, type segments pivotally supported to move about a fixed axis and each having a set of fixed numeral types thereon, general-operator-controlled means for differentially moving the segments to present types in accordance with the setting of the numeral keys in a common print- 105 110 115 120 125 130

ing plane wherein the type face rearwardly, a platen, a vibratable support for the platen, general-operator-controlled-means for vibrating the support to move the platen against types in the impression plane and retract the platen to expose the impression, means for supporting and feeding an inked ribbon between the platen and the printing plane close to the printing plane operable by vibratory movements of the platen support and mounted independently thereof, and means for guiding a work piece over the front of the platen to move therewith to and from the printing plane.

15 20. In a key-set adding and listing machine, the combination of a general operator for the machine, numeral keys, type segments pivotally supported to move about a fixed axis and each having a set of fixed numeral types thereon, general-operator-controlled means for differentially moving the segments to present types in accordance with the setting of the numeral keys in a common printing plane wherein the type face rearwardly, 25 a platen, a vibratable support for the platen, general-operator-controlled means for vibrating the support to move the platen against types in the impression plane and retract the platen to expose the impression, means for supporting and feeding an inked ribbon between the platen and the printing plane close to the printing plane operable by vibratory movements of the platen support and mounted independently thereof, means for guiding 30 a work piece over the front of the platen to move therewith to and from the printing plane, and means mounted partly on the platen support and partly independently thereof for line-spacing the work piece and 35 operable by vibratory movements of the platen support.

21. In a key-set adding and listing machine, the combination of a general operator for the machine, numeral keys, type segments 45 pivotally supported to move about a fixed axis and each having a set of fixed numeral types thereon, general-operator-controlled means for differentially moving the segments to present types in accordance with the setting of the numeral keys in a common printing plane wherein the type face rearwardly, 50 a platen, a vibratable support for the platen, general-operator-controlled means for vibrating the support to move the platen against types in the impression plane and retract the platen to expose the impression, means for supporting and feeding an inked ribbon between the platen and the printing plane close 55 to the printing plane operable by vibratory movements of the platen support and mounted independently thereof, means for guiding a work piece over the front of the platen to move therewith to and from the printing 60 plane, and means for rendering the platen 65

support vibrating means ineffective during operations of the general operator at will.

22. In an adding and listing machine, the combination of an oscillatable general operating handle for the machine, numeral types, type-setting means controlled by the operating handle, a pivoted platen support oscillatable about an axis extending transversely of the machine, a platen on said support, a pendent rock arm held to rock with said support in a plane extending fore-and-aft of the machine and having an open top slot therein, a member oscillatable by the operating handle in a plane extending fore-and-aft of the machine, a link pivoted at its forward end to said member, a stud on the rear end of said link normally engaged in said slot for rocking the rock arm rearward to move the platen toward set types, a spring for retracting the platen from the types, a key plunger guided for up-and-down movement and having a longitudinal slot intermediate its ends, a lever extending fore-and-aft of the machine and pivotally supported between the key plunger and the rear end of said link and extending rearward under said stud on the link, a stud on the forward end of the lever normally engaged in the bottom of the slot in the key plunger, a coil spring connected at its upper end with the stud on the lever and at its lower end with the key plunger, and a second coil spring attached at its upper end to a fixed part of the machine and at its lower end with said stud on the lever, said plunger having a non-print key at its upper end, and said lever being rockable when the non-print key is depressed to a position in which the rear end thereof holds said stud on the link out of the open top slot in the rock arm during actuation of the operating handle.

23. In an adding and listing machine, the combination of a general operator, numeral keys, numeral types, means controlled by the general operator for positioning types in accordance with the setting of the numeral keys, side by side in a common printing plane, a rotatable platen, a pivotally mounted support in which the platen is journaled, means controlled by the general operator for rocking the support to move the platen to and from the printing plane for taking impressions from types positioned in said plane, means for supporting a roll of paper adjacent the pivotal axis of the platen support and parallel therewith, means for guiding paper from the roll over the platen to move with the platen to and from the printing plane, and line-spacing means operable upon an actuation of the general operator for rotating the platen to unreel paper from the roll.

24. In an adding and listing machine, the combination of a general operator, a platen, a platen support shiftable by the general operator to and from an impression taking position, numeral types, type-selecting nu-

meral keys, means whereby types corresponding with actuated numeral keys are presented side by side in a common impression-taking plane and restored after taking of an impression therefrom through actuation of the general operator, means for feeding an inked ribbon between the impression-taking plane of the types and the platen comprising ribbon feeding dogs mounted on the stationary framework of the machine independently of the platen support and operable by shifting movements of the platen support, and line spacing means comprising a line spacing dog mounted on the stationary framework of the machine independently of the platen support and operable by the shifting movements of the platen support for advancing an impression taking piece over the platen.

25. In an adding and listing machine, the combination of a main frame, numeral keys, types mounted on the main frame and settable at a common printing line in accordance with the setting of numeral keys of the machine, a rocking platen support mounted on the main frame, a platen journaled on said support, means mounted on the main frame for rocking the support to shift the platen toward and from the set types for taking an impression from the types, means on the platen support for guiding a work-piece over the platen to move with the platen against set types, means for rotating the platen to line-space the work-piece operable by the platen support, and comprising a pawl pivoted on the main frame and a ratchet wheel held to the platen and rotatable by said pawl, and means for feeding an inked ribbon between the platen and set types operable by the platen support and comprising a pawl and ratchet spool rotating means mounted on the main frame.

26. In an adding and listing machine, the combination of a main frame, numeral keys, types mounted on the main frame and settable at a common printing line in accordance with the setting of numeral keys of the machine, a rocking platen support mounted on the main frame, a platen journaled on said support, means mounted on the main frame for rocking the support to shift the platen toward and from the set types for taking an impression from the types, means on the platen support for guiding a work-piece over the platen to move with the platen against set types, means for rotating the platen to line-space the work-piece operably by the platen support, comprising a pawl pivoted on the main frame and a ratchet wheel held to the platen and rotatable by said pawl, means for feeding an inked ribbon between the platen and set types operable by the platen support and comprising pawl and ratchet spool rotating means mounted on the main frame, and means on the main frame for

supporting a reeled, unset supply of the work-piece adjacent the pivotal axis of the rocking platen support for unwinding by the line-spacing mechanism.

In testimony whereof I hereunto affix my signature.

GLENN J. BARRETT.
